J. L. LATTA

PNEUMATIC PUMP

Filed Feb. 24, 1926

J. L. Latta,
By J. Hanson Boyden,
Attorney.

UNITED STATES PATENT OFFICE.

JOHN L. LATTA, OF HICKORY, NORTH CAROLINA.

PNEUMATIC PUMP.

Application filed February 24, 1926. Serial No. 90,369.

This invention relates to pneumatic pumps such as are used in rural districts for delivering fresh water from a well direct to a faucet without the intervention of any storage tank.

Specifically, the present invention is an improvement upon or further development of the construction shown in my prior Patent No. 1,502,253, granted July 22, 1924.

Among the objects of the present invention are to provide an improved water inlet valve, an improved air admission valve and associated parts, and an improved construction of exhaust valve operating motor.

In order that the invention may be readily understood, reference is had to the accompanying drawing forming a part of this specification and in which:—

Figure 1 is a vertical sectional view through my improved pump complete, parts being shown in elevation and parts being broken away;

Figure 2 is a transverse section through the pump substantially on the line 2—2 of Figure 1;

Figure 3 is a longitudinal central section on an enlarged scale of my improved exhaust valve operating motor piston;

Figure 4 is a vertical central section on an enlarged scale through my improved water inlet valve; and

Figure 5 is a fragmentary side elevation on an enlarged scale showing my improved air admission valve.

Referring to the drawing in detail, my improved pump, as in my prior patent, comprises a vertically arranged cylinder 1 closed at its upper end by a head 2 and at its lower end by a head 3. While in my prior patent the water inlet valve was carried by this lower head, it will be observed that in the present construction the lower head 3 is solid or imperforate.

The upper head 2 is similar in construction to that of my prior patent and comprises lower and upper sections 4 and 5 having registering ports or passages therein and joined by means of a suitable packing 6. It will be understood that the cylinder body and heads are held together by means of suitable rods or stay bolts (not shown).

Set into the top of the upper section 5 of the head 2 are an air supply pipe 7 and water delivery pipe 8 and an air exhaust pipe 9. Also opening out through the top of the upper section 5 is a water inlet port or pas-

sage 10, having its upper end covered by a wire screen 11 or the like and registering with a similar passage 12 formed in the lower section 4 of the head. Communicating with the pipe 8 are registering passages 13 and 14, in which passages at their junction point is arranged a check valve 15. Communicating with the pipe 7 are registering passages 16 and 17, and with the pipe 9 are 60 passages 18 and 19, all as clearly shown in Figure 1.

Depending downwardly into the cylinder from the head 2 and communicating with the passage 12 therein is a pipe 20 which 70 extends nearly to the bottom of the cylinder. To the lower end of this pipe is secured an inlet valve designated in its entirety by the numeral 21 and best shown in Figure 4. This valve comprises a block or 75 cap which is screwed on to the end of the pipe, and a valve seat in the nature of an annular grid structure 22, flat on its lower surface. Against this flat grid is adapted to seat a disk-like valve member 23 which is 80 preferably formed of soft rubber or the like and which is so constructed as to be buoyant when immersed in water. The valve member 23 is confined below its valve seat by means of a cage comprising a plate 24 supported by posts 25. From the above described construction it will be apparent that water entering the pipe 20 from above can flow freely through the grid 22 into the cylinder, but that when the valve member 85 90 95 23 has engaged, the grid return flow of water is prevented.

Depending from the head 2 and communicating with the passage 13 therein is a water discharge pipe 26. This also extends nearly to the bottom of the cylinder but preferably terminates slightly above the lower end of pipe 20. The bottom of this pipe 26 is entirely free and open.

Also depending from the head 2 and communicating with the passage 16 therein is an air supply pipe 27. This extends down almost as far as the pipe 26 and carries at its lower end an admission valve, the details of which are best shown in Figure 5. This 100 device comprises a cap 28 which is screwed on to the end of pipe 27 and is provided with a central port 29 communicating with such pipe. Adapted to cooperate with the port 29 is a valve member having a conical head 30 105 and a shank 31, such shank being loosely held and supported by a block 32 pivoted

at 34 to the cap 28. The extent to which the valve member projects above the block 32 is determined by an adjusting screw 33 against which the lower end of the shank 31 rests. It will be understood that this shank has a certain amount of "play" in the socket in which it is held, so that, when the block 32 is swung upon its pivot 34, the valve head 30 may suitably adjust itself to the edge of the port 29 and thus tightly close the same.

Secured to the block 32 and extending out therefrom beyond the pivot 34 is an arm or lever 35. This is so proportioned and positioned as to be engaged by a button 36 secured to the lower end of a vertical push rod 37. This push rod is mounted inside of a pipe 38, the lower end of which is offset as indicated at 38^a, an opening in the under side of this pipe being provided through which the rod 37 extends, such opening being closed by the button 36 when the parts are in the position shown in Figure 1. The rod 37 is relatively light and is capable of sliding vertically within the pipe 38. The block 32 is so proportioned and pivoted that it acts as a counterweight to sustain and balance the weight of the arm 35 and push rod 37 so that, regardless of existing pressures, the parts will remain in the position shown in Figure 1.

The pipe 38 is secured at its upper end to the lower end 39 of a water box or float chamber 40, preferably cylindrical and attached at its upper end to the section 4 of the cylinder head. The box or tube 40 forms a continuation of a cylindrical bore 41 formed in section 4 of the head.

Within the chamber formed by the bore 41 and tube 40 is housed a float 42. This is preferably in the nature of a cylindrical billet having a wooden core covered with soft rubber or the like. The upper end of this billet when in its elevated position, as shown in Figure 1, is adapted to engage and cover a port 43 forming the mouth of a passage 44. This passage communicates at its other end with the space above a perforated plate 45 forming the upper end or head of a cylinder 46 constituting part of the exhaust valve operating motor. This cylinder fits within a similarly shaped bore or cavity in the section 4 of the head 2.

In the lower end of this bore or cavity is fitted a member 47 which forms the head of the exhaust valve operating motor and which has a hollow extension 49 which projects downwardly into the pump cylinder and constitutes a seat for the exhaust valve. The port 18 in the cylinder head communicates with the cylinder of the exhaust valve operating motor below the piston thereof, and a port 48 formed in the member 47 establishes communication between the passage 18 and the interior of the pump cylinder when the exhaust valve is away from its seat.

This exhaust valve, as in my prior patent, preferably consists of a buoyant ball 50, and is confined by means of a tubular cage 51 surrounding the valve seat 49 and provided with air holes 52 spaced above the bottom 70 of the cage such a distance as to prevent the flow of air from lifting the ball toward its seat.

Fitted to reciprocate within the cylinder 46 is a piston comprising a cup leather 53 supported on a plate 55 and clamped thereto by means of a bolt 54 which engages the upper end of a hollow piston rod 57. A port 56 extends through the bolt 54 and establishes communication between the space above the piston and the interior of the hollow piston rod 57. Communication is further established from the interior of this hollow piston rod to the interior of the main pump cylinder, when the exhaust valve is 85 unseated by means of a port 58 opening through the side of the piston rod 57.

Mounted to slide freely within the hollow piston rod 57 is a plunger 60 pressed downwardly by a spring 59 and secured to a shank 61 which extends down beyond the end of the piston rod 57 and preferably carries at its end a knob or button 62. It will be clear from the above description that when the plunger 60 is moved upwardly into the bore of the hollow piston rod 57, it serves to obstruct and close the port 58, thus constituting a valve.

Having described in detail the structure of my improved pump, its operation will be clear from the following. The pump is, of course, submerged in the water or other liquid so that when there is no air pressure inside of the cylinder, water will flow by gravity through the passages 10 and 12 and pipe 20 into the cylinder, passing freely through the check valve 21 at the bottom of the pipe 20. Such flow will continue until the cylinder is practically full. Meanwhile the flow of compressed air from the pipe 7 into the cylinder is prevented by reason of the fact that the floating billet 42 rests upon the knob 37^a on the upper end of the push rod 37 and its weight is sufficient to hold the block 32 in its elevated position with the valve member 30 covering the port 29 and thus shutting off the air supply. When the water level reaches the top of the cylinder it fills the float chamber and causes the billet 42 to float up off of the push rod 37 and up against the port 43 as shown in Figure 1. The water has also carried the floating ball 50 up into engagement with the seat 49, thus closing the exhaust port, as shown in the drawing.

As soon as the push rod 37 is relieved of the weight of the billet 42, the air pressure in the pipe 27 forces the valve 30 away from the port 29, thus admitting compressed air into the cylinder. This air thereupon 120

rushes in, passing up through the water in the form of extremely fine bubbles which results in a thorough aeration of the water. The air pressure accumulating in the upper 5 end of the cylinder then serves to force the water up through the discharge pipe 26, past the check valve 15 and out through the delivery pipe 8.

As the air continues to enter the cylinder 10 the water is continuously expelled, the level gradually falling until it reaches the lower end of pipe 38 (which is slightly above the lower end of pipe 26). It may be noted at this point that on account of the button 36 15 closing the opening in the pipe 38 through which the rod 37 passes, the water seal on such pipe is not broken until the water level clears the lower end thereof. When this occurs the water immediately is discharged 20 from the pipe 38 and water box 40, thus permitting the billet 42 to fall. This falling movement of the billet simultaneously performs two functions. It results in pushing the rod 37 downwardly thus bringing the 25 valve 30 into engagement with the port 29 and shutting off the air supply, and at the same time it serves to open the port 43, thus admitting pressure fluid into the space above the piston 53. This piston therefore immediately moves downwardly against the tension of spring 63 and brings the knob 62 into engagement with the ball or exhaust valve 50. Meanwhile pressure fluid has begun to escape through the port 58, but as soon as 30 the button or shoe 62 engages the ball 50 the plunger 60 is forced up into the piston rod 57, thus covering the port 58 and preventing further escape of fluid therethrough. The continued downward movement of the piston 35 53 results in forcing the plunger 60 still further up into the piston rod, thus compressing the spring 59 until its tension is sufficient to dislodge the ball 50 from its seat. When this occurs the ball will be 40 thumped or thrown violently downward as the spring 59 expands, thus quickly projecting it out of the path of the air which rushes up through the exhaust ports 52. It will, of course, be understood that this 45 exhaust air passes up through the hollow member 49 and thence through the ports 48 and passages 18 and 19, sufficient clearance being provided between the piston rod 57 and the surrounding parts to permit the free escape of the air. The plunger 60 and associated parts, it will be seen, serve the double 50 function of acting as a valve to close the port 58 and at the same time serving to protect the exhaust valve out of the path of the escaping air. The purpose of the port 58 and passage 56 is to permit the escape of any water which may be trapped above the piston 53. As soon as the exhaust valve 50 leaves its seat, the pressure in the entire 55 pump is relieved and the spring 63 returns

the piston 53 to its normal position, as shown in Figure 1.

What I claim is:—

1. In a pneumatic pump, the combination with a vertical cylinder having motive fluid admission and exhaust valves, of a head at the upper end thereof, said head having both liquid inlet and outlet passages formed therein, and a pair of pipes carried by said head and extending downwardly into said cylinder to a point near the bottom thereof, 70 said pipes communicating with said inlet and outlet passages, respectively, and a constantly submerged check valve controlling the inlet passage pipe. 75

2. In a pneumatic pump, the combination with a vertical cylinder having motive fluid admission and exhaust valves, of a head at the upper end thereof, said head having both liquid inlet and outlet passages formed 80 therein, and a pair of pipes carried by said head and extending downwardly into said cylinder to a point near the bottom thereof, 85 said pipes communicating with said inlet and outlet passages, respectively, and a check valve controlling the flow of liquid through each pipe. 90

3. In a pneumatic pump, the combination with a vertical cylinder having motive fluid admission and exhaust valves and a liquid discharge port, of a liquid inlet pipe extending downwardly into the cylinder to a point below the low water level therein, and a check valve carried by said pipe at the lower end thereof. 100

4. A pneumatic pump comprising a vertical cylinder having liquid inlet and discharge passages, and a motive fluid exhaust valve, of a motive fluid admission valve located near the bottom of the cylinder, and 105 a float permanently located near the top of the cylinder for controlling said valve.

5. A pneumatic pump comprising a vertical cylinder having liquid inlet and discharge passages, and a motive fluid exhaust valve, of a motive fluid admission valve located near the bottom of the cylinder, a float chamber at the top of the cylinder, a free floating billet in said chamber, and means whereby said billet controls said motive 110 fluid admission valve. 115

6. A pneumatic pump comprising a vertical cylinder having liquid inlet and discharge passages, and a motive fluid exhaust valve, of a motive fluid admission valve located near the bottom of the cylinder, a float chamber at the top of the cylinder, a float in said chamber, means for maintaining said chamber full of liquid and the motive fluid admission valve open while liquid is being 120 expelled from the cylinder, until the cylinder is nearly empty, and means whereby, upon the escape of the liquid in said chamber, said float operates to close said motive fluid admission valve. 125

7. A pneumatic pump comprising a cylinder provided with liquid inlet and outlet passages and with air admission and exhaust valves, and exhaust valve operating motor, a float, and means whereby said float controls the supply of pressure fluid to said motor and also by its weight directly actuates the said air admission valve.

8. In a pneumatic pump, the combination with a vertical cylinder having water inlet and discharge passages and an air exhaust valve, of an air admission valve near the lower end of the cylinder, a lever for moving said valve, a vertically extending push rod engaging said lever, and a float at the top of the cylinder arranged to engage the upper end of said rod and operate said valve.

9. In a pneumatic pump, the combination with a vertical cylinder having water inlet and discharge passages and an air exhaust valve, of an air admission port near the lower end of the cylinder, a valve for closing said port, a pivoted block carrying said valve and provided with an extension, a push rod engaging said extension, and a float arranged to engage said push rod to operate the valve.

10. In a pneumatic pump, the combination with a vertical cylinder having water inlet and discharge passages and an air exhaust valve, of an air admission port near the lower end of the cylinder, a valve for closing said port, a pivoted block carrying said valve and provided with an extension, a vertically disposed push rod supported at its lower end on said extension, and a float arranged to engage the upper end of said rod and operate said valve, said block being so proportioned and pivoted as to constitute a counter weight to substantially balance the weight of said rod.

11. In a pneumatic pump, air admission means comprising a vertically disposed pipe, a cap at the bottom of said pipe provided with a port, a block pivoted to the

cap adjacent said port, a valve member loosely carried by said block and arranged to be brought into engagement with said port when said block is swung on its pivot, and float-controlled means for swinging said block on its pivot, to operate said valve.

12. A pneumatic pump comprising a cylinder having liquid inlet and outlet, and an air admission valve, a head closing the end of the cylinder and having an air exhaust passage and a motor chamber, an exhaust valve at the lower end of said chamber, an exhaust valve operating motor comprising a piston vertically reciprocable within said chamber, means for admitting fluid pressure above said piston to actuate the same, the piston rod having a passage therethrough establishing communication between the space above said piston and the interior of said pump, and a valve controlling said passage.

13. A pneumatic pump comprising a cylinder having liquid inlet and outlet, and an air admission valve, a head closing the end of the cylinder and having an air exhaust passage and a motor chamber, an exhaust valve at the lower end of said chamber, an exhaust valve operating motor comprising a piston vertically reciprocable within said chamber, means for admitting fluid pressure above said piston to actuate the same, the piston rod having a passage therethrough establishing communication between the space above said piston and the interior of said pump, and a spring-pressed plunger mounted within and projecting below the end of said piston rod, said plunger constituting a valve to control the said passage, the engagement of said plunger with the exhaust valve as the piston moves downwardly, serving to shift the plunger to cause it to close said passage.

In testimony whereof I affix my signature.

JOHN L. LATTA.
